UNITED STATES PATENT OFFICE.

ORSON J. BLAKESLEY, OF DENVER, COLORADO, ASSIGNOR TO THE BLAKESLEY KEYLESS LOCK COMPANY, OF DENVER, COLORADO.

KEYLESS LOCK.

No. 866,567.

Specification of Letters Patent.

Patented Sept. 17, 1907.

Application filed August 14, 1905, Serial No. 274,060. Renewed January 26, 1907. Serial No. 354,316.

To all whom it may concern:

Be it known that I, ORSON J. BLAKESLEY, a citizen of the United States, residing at the city and county of Denver and State of Colorado, have invented certain new and useful Improvements in Keyless Locks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in locks of the class in which keys as ordinarily understood are not employed. It also belongs to the class of locks in which a number of instrumentalities must be actuated in order to release the bolt or other locking part.

My present invention as illustrated in the drawing and herein described is more especially intended for use as a bicycle lock and is of such construction that the user may operate it in the dark without any difficulty. This device as shown in the drawing is made in circular form. One end of a chain is secured thereto while to the other end of the chain is attached a bolt or device which when inserted in the casing is automatically locked in place. A series of pins protrude from the periphery of the circular casing and the mechanism may be so set as to require that certain of these pins must be pressed in order to release the bolt or hasp. The mechanism is so constructed that the predetermined pins must be alone pressed in order to release the bolt; while if other pins are pressed the device will only be more securely locked. From what has already been said it will be understood that the mechanism may be set for any desired combination, making it necessary that the person who opens the lock must understand this combination.

Having briefly outlined my improved device as well as the function it is intended to perform, I will proceed to describe the same in detail reference being made to the accompanying drawing in which is illustrated an embodiment thereof.

In this drawing, Figure 1 is a top plan view of my improved device. Fig. 2 is an edge view of the same. Fig. 3 is a horizontal section taken through the casing with the top plate removed. This section is taken between the stationary and movable disks of the lock mechanism with the parts shown on a larger scale than in Figs. 1 and 2. Fig. 4 is a cross section taken on the line 4—4 Fig. 3, the pins, however, being shown in elevation. Fig. 5 is a top plan view of the device similar to Fig. 1 but with the top plate partly broken away and the depending lip thereof sectionized. Fig. 6 is a section taken on the line 6—6 Fig. 7 with all of the parts

in place. Fig. 7 is a plan view of the body of the casing with all of the mechanism removed except the revoluble ring for locking the cap in place. Fig. 8 is a detail view partly in section of the movable disk. This is an underneath view of the disk or shows the same with its lower face turned upwardly or in the position 60 the reverse from that shown in Figs. 4, 5 and 6, but on the same or approximately the same scale. Fig. 9 is a perspective view in detail and on a larger scale of one of the spring-actuated tumblers or pieces which must be actuated in order to unlock the mechanism. Fig. 10 65 is a fragmentary detail view of the movable disk. Fig. 11 is a similar view of the same viewed from a different position.

The same reference characters indicate the same parts in all the views.

Let the numeral 5 designate a casing which incloses the lock mechanism. This casing as shown in the drawing is circular in shape and provided with two flat faces. It is in reality composed of two members, 6 being the body member and 7 a cap. The body of the casing is provided with a circular outer wall 8 internally shouldered as shown at 9 to receive the outer edge of the cap 7. The body of the casing is also provided with an annular flange 10 which is provided at two opposite points with sockets 11 open at the top to receive studs 12 fast on the cap 7. Surrounded by the annular flange 10, is a disk 13, which is secured to the body of the casing by a pin 14. This disk is provided with a central opening through which passes a post 15. The disk is also provided with radial slots 16 terminating at their inner extremities in an annular recess 17 surrounding the post 15. These slots 16 form guides for the inner reduced extremities of pins 18 whose outer extremities 19 protrude exteriorly from the peripheral wall 8 of the body of the casing. Inside of the wall 8 each pin is shouldered as shown at 20 and its reduced portion 21 is surrounded by a coil spring 22 located between the shoulder 20 and the annular flange 10 of the body of the casing. The tendency of this spring 22 is to hold its pin 18 at its outward limit 95 of movement. Each pin is provided adjacent the shoulder 20 with a stop 23 which limits the outward movement of the pin in response to the recoil of the spring 22. The parts 19 and 21 of each pin 18, fit closely in openings formed in the peripheral wall 8 and the annular flange 10 respectively, of the body of the casing. Protruding inwardly beyond the annular flange 10, each pin is provided with a shouldered part 24 and beyond this shouldered part is the reduced portion 25 which enters a slot 16 of the disk 13. The shoulders 26 of each pin limit the inward movement thereof in response to inward pressure on the protruding head 19 of the pin. Certain of the pins 18 are pro-

vided with detachable projections 27 located substantially on the line between the parts 24 and 25 whereby each projection when its pin is forced to its inward limit of movement, enters a slot 28 formed in 5 a movable disk 29. These slots 28 are enlarged at their inner extremities as shown at 30, there being as many slots 28 in the disk 29, as there are slots 16 in the stationary disk 13.

Located in front of the inner extremities of certain 10 of the pins 18, are what I will term tumblers 31 having reduced lower portions 32 adapted to fit into the radial slots 16 of the disk 13. The central recess 33 of the disk 29 is considerably larger than the central recess 17 of the disk 13. The upper enlarged portion 34 of the 15 tumblers 31, is adapted to enter the recess 33 of the disk 29 when the pins 18 corresponding with the tumblers 31 are pushed inwardly. Normally the outer extremities 35 of the tumblers which are beveled for the purpose, enter the enlarged inner extremities of 20 the slots 28, and lock the disk 29 from movement. The pins 18 which act upon the tumblers, are not provided with the removable projections 27. In other words when the tumblers 31 are placed in position forward of certain of the pins 18, the projections 27 which are 25 preferably composed of screws, are removed. The normal position of the pins 18 is such that the projections 27 do not enter the slots 28 of the removable disk 29. As just stated, however, the normal position of the pins 18 is such that the outer extremities of the 30 tumblers 31 are allowed to enter the slots 28 of the disk 29. The tumblers are held at their outer limit of movement, by means of coil springs 36 which surround the reduced inner extremities 37 of the tumblers 31. These springs are located between the 35 shoulders 38 on the tumblers and the post 15 of the body of the casing.

As the pins 18 which act on the tumblers 31 are moved inwardly, the tumblers are actuated sufficiently to disengage them from the slots 28 of the disk 29, where- 40 by the latter is free to move or turn on the post 15 within certain limits. The disk 29 is provided with an arm 39 which projects outwardly, terminating just within the peripheral wall 8 of the casing. This arm is provided with a leaf spring 40 one portion of which acts on a dog 45 41 movably mounted in an opening formed in the arm 39. This dog 31 is held in place by a pin 42 passing through a slot 43 formed in the dog. Another part of the spring 40, passes around the outer extremity of the arm 39 and stands out from the arm as shown at 44 but 50 occupying a lower plane than the protruding extremity of the dog 41. The arm 39 is provided with a recess 45 in which the protruding extremity of the dog 41 and the spring part 44 are located.

The disk 13 is provided on its under side with a cir- 55 cumerential recess in which is located a ring 46 having exteriorly protruding lugs 47 adapted to enter the sockets 11 of the annular flange 10 and engage circular grooves 48 formed in the studs 12, whereby the cap 7 is locked in place on the body of the casing. In order to 60 permit the ring 46 to be manipulated from the outside of the casing, this ring is provided with an arm 49 whose outer extremity protrudes through an opening formed in the peripheral wall of the casing, this protruding extremity occupying a position below a depending projec- 5 50 tion 50 attached to the cap, this projection 50 occupying

a position flush with the outer surface of the peripheral wall 8. This projection 50, however, does not fill the opening in the peripheral wall of the casing since sufficient space is left below it for the arm 49 which is accessible from the outside; and for the bolt 54 as hereinafter 70 explained. This protruding extremity of the arm 49 is notched or toothed as shown at 51 to facilitate manipulation. When the ring is moved to the position shown by dotted lines in Fig. 7, the cap is unlocked and may be removed whereby the interior mechanism of the 75 lock casing is exposed.

As shown in the drawing a chain 52 is secured to the outer wall of the casing as shown at 53. To the opposite extremity of this chain is attached a bolt 54 having an opening 55 adapted to receive the protruding extremity 80 of the dog 41, when the bolt is inserted through an opening left in the peripheral wall of the body of the casing therefor. This bolt when in position prevents the movement of the arm 49, hence the cap cannot be released by the ring 46, until after the device has been unlocked and the bolt removed. When it is desired to insert the bolt, the arm 49 of the locking ring must be in the position shown in Fig. 3 or in the position to lock the cap in place, since the depth of the bolt 54 is equal to the entire depth of the opening in the peripheral wall of 90 the casing in which the bolt is inserted. When the bolt is in position as shown in Fig. 5, the dog 41 enters the recess 55, while the part 44 of the spring is placed under tension by the solid portion of the bolt. The tendency of the part 44 of the spring acting on the bolt which 95 forms an abutment, is to move the disk 29 away from the bolt in the direction to release the latter from the dog 41. This it cannot do, however, as long as the tumblers 31 are in their normal position or engaging the inner extremities 30 of the slots 28 formed in the disk 29 100 as heretofore explained. When, however, the pins 18 corresponding with the tumblers 31 are pressed inwardly whereby the tumblers are actuated sufficiently to release their extremities 35 from the slots 28 of the disk 33, the spring part 44 acts on the bolt 54 to turn the 105 disk 29 sufficiently to cause the dog 41 to release the bolt 54. A leaf spring 56 now acts on the inner extremity of the bolt 54, with sufficient force to throw the bolt automatically out of the casing. When the disk 29 is thrown to the position to release the bolt from the dog 41, the arm 39 of the disk is brought into engagement 110 with a spring 57 which is placed under sufficient tension to return the disk 29 to its normal position as soon as the bolt 54 is thrown out of the casing as heretofore explained. As soon as the bolt 54 escapes from the casing, 115 the pins 18 which have been forced inwardly to operate the tumblers, are released from pressure. When this is done the tumblers of the lock are actuated by their springs 36 to cause the tumblers to engage the enlarged portions 30 of the slots 28 belonging to the disk 29, thus 120 locking the disk against movement in response to the tension of the spring part 44.

From the foregoing description the use and operation of my improved lock will be readily understood. When a chain is used in connection with the lock, the chain is 125 passed through or around the article to be protected or connected therewith in any suitable manner, after which the bolt 54 is inserted to the position shown in Fig. 5 whereby the dog 41 enters the opening 55 of the bolt, the latter acting on the spring part 44 to place the 130

latter under tension. Now if it is desired to release the bolt, the pins 18 in line with the several tumblers 31, are pressed inwardly whereby corresponding movement is imparted to the tumblers of sufficient degree to 5 release the disk 29 allowing the tension of the spring part 44 to move the disk sufficiently to release the bolt from the dog 41. As soon as this occurs the leaf spring 56 acts on the bolt with sufficient force to throw the latter out of the casing. The movement of the disk 29 has 10 been sufficient to cause its arm 39 to engage the spring 57 and place the latter under sufficient tension to return the disk to its original or locking position and when the tumblers 31 again engage it in the locking relation.

The tumblers 31 are readily removable whereby the 15 combination of the lock may be changed at any time desired. In order to accomplish this it is only necessary to remove the cap 7 and the disk 29 which makes the tumblers accessible. When any tumbler is changed from its position in front of one pin to its position 20 in another pin, the screw projection 27 is removed from the pin which is to actuate the tumbler and inserted in the pin from which the tumbler has been removed. It is evident that one or more of the tumblers may be changed at pleasure thus requiring the inward 25 movement of different pins in order to release the locking disk. When these tumblers are changed it is only necessary for the user to take note of the particular pins required to be pressed in order to actuate the tumblers. The locking disk and cap are then replaced in their 30 respective positions when the lock is ready for use.

Having thus described my invention, what I claim is:

1. In a lock, the combination of a casing and a bolt or hasp, a locking part movably mounted therein, and a number of spring-held pins movably mounted in the casing and protruding therefrom, certain of the pins normally holding the locking part against movement when in the bolt locking position, the locking part being released when the pins are pressed; while certain other pins normally disengaged from the locking part, when pressed engage the 40 same to hold it against movement, and means acting on the locking part for automatically moving it to the unlocked position and back again to the locked position as soon as the said locking part is released by the inward pressure of the first named pins.

45 2. In a lock, the combination of a casing and a bolt or hasp, a locking disk movable in the casing and normally under spring tension to move it to the unlocked position, spring-held pins movable in the casing and having their outer extremities exposed to facilitate manipulation by 50 inward pressure, the said pins normally holding the disk against movement, but which when pressed inwardly release the disk and allow it to move in response to the spring tension acting thereon, and means for automatically returning the said disk from the unlocked to the locked position.

55 3. The combination of a casing, a spring-tensioned locking disk mounted therein and adapted to move in response to the tension acting thereon, to the unlocked position, a series of spring-held pins movable in the casing, their outer extremities being exposed whereby they may be pressed inwardly, tumblers normally locking the disk against movement, certain of the pins serving to actuate the tumblers to release the disk when the last named pins are pressed inwardly, and means for automatically returning the said disk to the locked position after it has assumed the unlocked position.

4. The combination of a casing, radially disposed spring-tensioned pins movable longitudinally in the casing, a disk having limited rotary action around the center of 70 the pins radiation, spring-actuated tumblers normally moved outwardly to lock the disk against movement, certain of the pins being arranged when pressed inwardly to re-

lease the disk; and means for automatically moving the disk when unlocked by the pins, to the unlocked position 75 and back to the locked position.

5. The combination of a casing, a locking disk movably mounted therein, spring-actuated tumblers normally acting on the disk to prevent movement, the casing having a circular outer wall and provided with an interiorly located 80 concentric flange, the outer wall of the casing and the flange having radially arranged registering openings, pins movable in said openings, springs acting on the pins to hold them in their outward limit of movement whereby their outer extremities are caused to protrude from the 85 casing, certain of the pins being arranged to act on the tumblers and release the latter from engagement with the locking disk when the pins are pressed inwardly; while other pins are arranged to engage the disk when pressed inwardly and lock it against movement, and means for 90 automatically moving the locking disk when released by the pins, to the unlocked position and back again to the locked position.

6. In a lock, the combination of a casing, a disk movably mounted in the casing and having an arm projecting outwardly from the body of the disk, the arm having a spring-held dog normally protruding into a passage registering with an opening formed in the outer wall of the casing, the said arm also having a spring protruding into the said opening, a bolt adapted to be inserted in the said opening and engaged by the dog, the bolt placing the spring under tension, means located within the casing and acting on the disk to hold it in position to lock the bolt in place, and means movably mounted in the casing, protruding therefrom and arranged when operated to act on the locking means and release the disk whereby the latter is allowed to move in response to the spring carried by its said arm, sufficiently to release the bolt from engagement with the dog, a spring located within the casing and acting on the bolt to throw it outwardly when released from the 100 dog, and another spring acting on the arm of the locking disk to return the latter to its normal position after the bolt has been removed from the casing.

7. The combination of a casing, a locking disk mounted to have a limited rotary movement in the casing, the said disk being provided with a locking arm projecting outwardly from the body of the disk and provided with a spring-actuated dog, the casing having a bolt opening in which the dog protrudes, a bolt adapted to be inserted in said opening and provided with an aperture engaged by 115 the dog, a spring acting on the bolt and having a tendency to throw the latter outwardly, another spring acting on the bolt and having a tendency to move the disk away from the bolt to release it from the dog, another spring arranged to be engaged by the arm of the disk when the latter is moved to the unlocked position and throw the disk back to the locked position, suitable means located within the casing for holding the disk in the locked position, and suitable means accessible from the outside of the casing for actuating the locking means to release the 120 disk and allow it to move to the unlocked position in response to the tension of its actuating spring.

8. In a lock, the combination of a casing having a circular outer wall, a stationary disk located in said casing and having radial grooves, a locking disk movably mounted above the stationary disk, the locking disk also provided with grooves, tumblers having parts engaging the grooves of the stationary disk, springs acting on the tumblers to cause their outer extremities to engage the grooves of the movable disk and lock the latter against movement, pins 135 radially disposed and longitudinally movable in the casing in line with the tumblers and adapted to actuate the latter to release the locking disk, and other radially disposed pins movable longitudinally in the casing and whose inner extremities enter the grooves of the stationary disk, the last named pins being normally disengaged from the locking disk but having parts adapted to engage the last named disk when the said pins are pressed inwardly, and means for automatically moving the locking disk when released, to the unlocked position and back again to the 140 locked position.

9. In a lock, the combination with a bolt or hasp, of a locking disk, means for holding the said disk in the lock-

ing position with reference to the bolt, and means for automatically moving the disk when released from the holding means, to the unlocked position and back again to its normal or locked position.

- 5 10. The combination with a bolt, of a locking disk engaging the bolt and movably mounted, means for holding the disk in the locked position with reference to the bolt, said means being capable of movement to release the disk, and means for automatically ejecting the bolt, throwing

the disk to the unlocked position and back again to the 10 locked position, as soon as the disk has been released from its holding means.

In testimony whereof I affix my signature in presence of two witnesses.
